DRIER

George C. Chapman, Modesto, Calif.

Application June 19, 1936, Serial No. 36,102

12 Claims. (Cl. 34—37)

This invention relates to driers and is particularly related to driers for a grain such as rice.

Rice is grown and harvested under moist conditions and is difficult to handle for storage and 5 milling purposes until thoroughly dry. Its moisture content when harvested is great and in order to dry it economically in commercial quantities there must be provided a drying means capable of providing in a simple and economic way a 10 large drying surface or area over which the rice moves during the drying operation.

Therefore it is the prime object of this invention to provide a gravity flow type of drier in which the drying screens are so arranged and 15 controlled as to allow a large volume of the grain to flow rapidly through the drier and at the same time to be subjected to a maximum drying air surface or area.

Another object is to provide a means for easily 20 altering the speed of movement of the grain through the air stream and for also agitating the grain as it thus moves.

A further object of the invention is to produce 25 a simple and inexpensive device and yet one which will be exceedingly effective for the purpose for which it is designed.

These objects I accomplish by means of such 30 structure and relative arrangement of parts as will fully appear by a perusal of the following specification and claims.

In the drawings similar characters of reference indicate corresponding parts in the several views:

Figure 1 is a side elevation of the apparatus.

Figure 2 is an enlarged fragmentary section of 35 the lower portion of the machine.

Figure 3 is a fragmentary side view of a screen shaker and adjusting arm unit.

Figure 4 is a top plan view of the same.

Referring now more particularly to the characters of reference on the drawings, the apparatus 40 comprises a vertical relatively tall casing of rectangular cross section open only at the top, and forming an enclosure in which the grain receiving screens are mounted.

Extending substantially from front to back 45 of the casing and disposed in vertically spaced relation are symmetrically arranged pairs of screens 2.

The screens of each pair are close to each 50 other along adjacent edges, and are disposed with a downward diverging slope to their opposite edges, which clear the sides of the casing a certain distance. Said screens are pivoted in common on a rod 3 or the like supported at its 55 ends on the central vertical frame members 4

of the casing. A feed chute 5 is mounted to deliver evenly onto the topmost pair of screens.

Mounted in the casing between the pairs of screens 2 are other pairs of screens 6, disposed in the reverse relation to the screens 2. In other words, the screens 6 of each pair are pivoted at their upper opposite edges on the corner frames 8 of the casing as at 9, and converge with a downward slope to their adjacent edges. With this arrangement, the screens 2 discharge onto the 10 screens 6 adjacent the upper pivoted edges of the latter, and the screens 6 in turn discharge onto the screen 2 adjacent the upper pivoted edges thereof.

The lowermost screens 2 discharge into a bin 15 10 of screen or other perforated material which extends at its top over the entire cross sectional area of the casing, and then converges to a central outlet spout 11 at the bottom, which is some 20 distance above the bottom of the casing. The spout is normally closed by a gate 12 operable from exteriorly of the casing, and discharges into a gate-controlled chute 13 leading to the exterior of the casing.

Vertical baffles 14 project upwardly from the 25 screens 2 at their topmost edges, and serve to positively deflect the grains rolling down the screens 6 onto the corresponding screens 2 below. Also these baffles tend to break up or 30 separate the grains striking the baffles, and which grains may be stuck together in lump form due to their dampness.

A blower 15 is mounted exteriorally of the 35 casing, its outlet 16 discharging the air at a natural or artificial heat, into the casing below the bin 10. Since the air can only then escape from the top of the casing, and to reach said top must pass through the bin and through the series of screens above the same, it will be seen that the grain or other produce in the bin, as well as that on the screens or falling from one to the other, is subject to the constant drying influence of the upwardly moving blast of air.

It will be noted that the screens overlap each 40 other for substantially their entire area, thus providing for a maximum drying area in a drier of a given size, since the greatest drying action of course takes place while the grain is on the screens.

Inasmuch as the drying action, with a given air 45 temperature, depends on the speed of travel of the grain or other produce from top to bottom of the casing, and which speed is determined by the slope of the screens, it is desirable to be able to alter such slope to suit the drying requirements 50

of the produce. It is also desirable that the screens be agitated irrespective of their slope, in order to agitate the produce thereon to better separate the same and expose the maximum areas 5 of their surface to the drying action.

This adjustment and agitation is accomplished as follows:

All the screens, on both sides, are connected intermediate their ends by substantially vertical links 17. Other links 18 are connected to and depend from the bottom pair of screens 2, the links 18 on each side depending between the adjacent side of the casing and bin and converging to a common pivot pin 19.

15 A block 20 is mounted on this pin, the block sliding between vertical guides 21 secured to the casing wall.

An arm 22 is connected to the pin 20, and carries a strap 23 on its lower end which engages an eccentric 24. The eccentric is fixed on a stub shaft 25 journaled in the outer end of a substantially horizontal arm 26, which at its opposite end is turnable on a horizontal driven shaft 27 disposed in the casing under the bin and parallel to the pivots of the screens.

Since there are two sets of the links 18—one on each side of the screens—there are two arms 26 and adjacent parts as above described, both arms however being mounted on the one shaft 27. 30 Drive connections such as chain drives 28 between the shaft 27 and the stub shafts 25, cause the eccentrics to be rotated. This of course raises and lowers the arms 22, and imparts a short vertical stroke to the various links, with a corresponding vertical agitation of the screens.

From the above described arrangement of parts, it will of course be evident that if the arms 26 are turned up or down about the shaft 27, the angular setting or slope of the screens will be 40 altered without interfering with the agitating thereof.

To thus turn both arms from one side of the casing, I provide another shaft 29 disposed parallel to shaft 27, and adapted to be rotated by 45 means applied to one end thereof such as a worm gearing 30. Gears 31 fixed with the arms 26 axially of shaft 27 mesh with pinions 32 secured on shaft 29.

From the foregoing description it will be readily seen that I have produced such a device as substantially fulfills the objects of the invention as set forth herein.

While this specification sets forth in detail the present and preferred construction of the device, 55 still in practice such deviations from such detail may be resorted to as do not form a departure from the spirit of the invention, as defined by the appended claims.

Having thus described my invention what I 60 claim as new and useful and desire to secure by Letters Patent is:

1. A drier comprising comprising a vertical casing, means to blow air longitudinally through the casing, a plurality of vertically spaced screens in 65 the casing disposed in transversely staggered relation and adapted to successively discharge onto each other from the topmost one down, pivot mounting means for the screens at their opposite ends in alternating order, means applied to the 70 screens to turn them on their pivots to set them at different selected slopes, and means formed in part with said last named means to oscillate the screens about their pivots through an arc of constant length irrespective of the adjusted position 75 of the same.

2. A drier comprising a vertical casing, means to blow air longitudinally through the casing, a plurality of vertically spaced screens in the casing disposed in transversely staggered relation and adapted to successively discharge onto each other from the topmost one down, pivot mounting means for the screens at their opposite ends in alternating order, means applied to one screen to turn it on its pivot whereby to adjust it at a predetermined slope, and substantially vertical links connecting the screens intermediate their ends whereby all the screens will be adjusted with the movement of the one screen. 5

3. A structure as in claim 2, with means formed in part with said screen turning means to impart an agitating movement to the screens irrespective of the turning of the screens to adjust the same. 15

4. In a drier, a substantially horizontal screen, a pivot mounting for one end of the screen, means applied to the screen to turn the same on its pivot to adjust the slope thereof, and means formed in part with said screen turning means to oscillate the screen about its pivot through an arc of constant length irrespective of its adjusted 20 position. 25

5. In a drier, a substantially horizontal screen, a pivot mounting for one end of the screen, a substantially vertical supporting member connected at one end to the screen, a substantially horizontal arm, a strap on the other end of the member, an eccentric turnably mounted on one end of the arm and engaging the strap, a pivot mounting for the opposite end of the arm, means to turn the arm, on its pivot and means to rotate the eccentric irrespective of the turning of the arm. 30 35

6. In a drier, a substantially horizontal screen, a pivot mounting for one end of the screen, a substantially vertical supporting member connected at one end to the screen, a substantially horizontal arm, a strap on the other end of the member, an eccentric turnably mounted on one end of the arm and engaging the strap, a driven shaft on which the opposite end of the arm is turnable, a drive connection between the shaft and the eccentric, and separate means to control the turning of the arm. 40 45

7. A drier comprising a vertical casing, means to blow air longitudinally through the casing, a plurality of vertically spaced pairs of screens arranged in symmetrical relation in the casing and sloping downwardly to terminations adjacent but spaced from the opposite sides of the casing from their upper adjacent ends, other pairs of screens in the casing disposed intermediate the first named screens, and sloping downwardly from the opposite sides of the casing to terminations spaced from each other, whereby produce fed onto the topmost screens will be discharged from the same at their lower end onto the adjacent screens below adjacent the top thereof, and from said last named screens at the bottom thereof onto the screens immediately below adjacent the top thereof and means to feed produce evenly onto the topmost pair of screens. 50 55 60

8. A structure as in claim 7, with a foraminous bin within the casing into which the lowermost screens deliver. 70

9. A structure as in claim 7, with vertical baffles projecting upwardly from the first named pairs of screens at the top thereof to a termination above the adjacent lower edges of the other pairs of screens. 75

10. A drier comprising a vertical casing, a plurality of vertically spaced screens in the casing disposed in transversely staggered relation and arranged to successively discharge onto each other from the topmost one down, means to feed produce to be dried onto the topmost screen, a foraminous bin in the casing into which the lowermost screen discharges, and means to blow air longitudinally of the casing through the bin and screens.

11. A structure as in claim 10, with controlled

outlet means from the bottom of the bin including a chute leading through one side of the casing.

12. In combination, a shaker screen, having a normal initial angle of setting, fixed pivot means supporting the screen, drive means applied to the screen to oscillate the same, and means formed in part with the drive means to alter said normal angle of the screen while the drive means is in operation.

GEORGE C. CHAPMAN.
